(57) **CLAIM**

The ornamental design for the welding and cutting machine for metals, as shown and described.

DESCRIPTION

1. Welding and cutting machine for metals

1.1 : Perspective

1.2 : Front

1.3 : Back

1.4 : Top

1.5 : Bottom

1.6 : Left

1.7 : Right

The broken lines shown in the drawings represent portions of the welding and cutting machine for metals that form no part of the claimed design.
